UNITED STATES PATENT OFFICE

147,836

DESIGN FOR AN AIRPLANE

Edward F. Burton, Los Angeles, and Carlos C. Wood, Brentwood Heights, Calif., assignors to Douglas Aircraft Company, Inc., Santa Monica, Calif.

Application March 23, 1946, Serial No. 127,844

Term of patent 14 years

(Cl. D71—1)

To all whom it may concern:

Be it known that we, Edward F. Burton and Carlos C. Wood, citizens of the United States and residents, respectively, of Los Angeles, in the county of Los Angeles and State of California, and Brentwood Heights, West Los Angeles, in the county of Los Angeles and State of California, have invented a new, original, and ornamental Design for an Airplane, of which the following is a specification, reference being had to the accompanying drawings, forming a part thereof:

Figure 1 is a bottom perspective view of an airplane in flight showing our new design.

Figure 2 is a side elevational view of subject airplane depicted in Figure 1 with the extended landing gear shown in dotted lines.

Figure 3 is a top plan view of the airplane depicted in Figures 1 and 2.

Figure 4 is a front elevational view of the airplane depicted in Figures 1, 2, and 3, with the landing gear thereof being shown in the extended position by dotted lines.

We claim:

The ornamental design for an airplane, substantially as shown.

EDWARD F. BURTON.
CARLOS C. WOOD.
